UNITED STATES PATENT OFFICE.

OTTO ROMANZE, OF TONSLEY HILL, WANDSWORTH, COUNTY OF SURREY,
ASSIGNOR TO MASON, THORNTON & ROMANZE, OF NO. 9 NORTH STREET,
WANDSWORTH, LONDON, ENGLAND.

ELECTRIC-ARC LAMP.

SPECIFICATION forming part of Letters Patent No. 330,351, dated November 10, 1885.

Application filed September 12, 1885. Serial No. 176,972. (No model.)

To all whom it may concern:

Be it known that I, OTTO ROMANZE, of 51
Tonsley Hill, Wandsworth, in the county of
Surrey, Kingdom of Great Britain, have in-
5 vented a new and useful Improvement in Elec-
tric-Arc Lamps, of which the following is a
full, clear, and exact description.

This invention relates to improvements in
electric-arc lamps, and particularly to the
10 mechanism whereby the upper carbon is auto-
matically fed down as fast as it is consumed.

Reference is to be had to the accompanying
drawings, forming part of this specification,
wherein Figure 1 is a front elevation, and
15 Fig. 2 a side elevation, partly in section, of
the entire lamp. Fig. 3 shows the auto-
matic feed mechanism as seen from the oppo-
site side to that shown in Fig. 2 and in a dif-
ferent position of the parts. Fig. 4 shows de-
20 tails of the lower-carbon holder.

The upper part of the lamp-frame consists
of a metal tube, A, having upon it two
flanges, B B', between which is wound a sole-
noid-coil, C, which is placed in the lamp-cir-
25 cuit by being connected at one end to the
terminal D, and at the other with the tube A.
The flange B has two oppositely-projecting
arms, B², to which the rods carrying the sup-
port for the lower carbon are fixed, but from
30 which they are insulated. Within the tube
A and solenoid C is a tubular soft-iron core,
E, which is capable of moving freely up and
down therein, being guided in this movement
by three small friction-rollers, e³, mounted on
35 its upper end and running against the interior
of the tube A. The extent of motion of the
core is limited to about the maximum length
of the arc it is desired to maintain by means
of an arm, e, projecting from the core and
40 having a hole embracing freely a screw-stud,
e', fixed to and projecting from the under side
of flange B, and provided with a nut, e², where-
by the downward motion of the core is adjust-
ably limited and the maximum distance be-
45 tween the carbons determined. The core is
also guided by another and opposite arm, e³,
sliding on a smooth pin, e⁴. The upward mo-
tion of the core is limited by the same arms
coming in contact with the flange B of the

frame. A portion of the weight of the core 50
and attached parts is sustained by springs f,
connected to the under side of flange B, and to
screws f', passing through arms projecting
from opposite sides of the core, near the lower
end, and provided with nuts f², whereby the 55
tension of the springs may be adjusted.

The upper carbon passes centrally through
the tubular core E, and is supported and fed
by the following mechanism carried by the
core: g h are two concave rollers placed in line, 60
one above the other, and mounted in a slot
in one side of the core at about two inches
apart, and i is a similar roller placed at the
opposite side of the carbon and opposite the
middle of the space between g and h, these 65
three rollers presenting their concave periph-
eries to the carbon and gripping it between
them. The core E is cut away at the lower
end at the side at which the roller i is situate,
and the axis of this roller is mounted in an 70
oscillating bell-crank frame, K, pivoted at K'
to the core E, so that the roller i can be moved
toward and away from the carbon by rocking
frame K on its pivot. A spring, l, is attached
to the core and to an adjusting-screw in the 75
outer end of the horizontal arm of the frame
K, whereby the roller i is caused to press
against the carbon sufficiently to prevent it
slipping by its own weight, the tension of the
spring being regulated by the screw. The 80
rotation of the roller i is controlled by an
escapement consisting of a scape-wheel, m, fast
on the axis of roller i, an anchor, n, engaging
with the wheel m, and a pendulum, o, fixed at
the opposite end of the anchor-arbor, whereby 85
the roller i is prevented from rotating too
rapidly, and thereby allowing the carbon to
descend too fast. The rotation of the roller i
and the feed of the carbon are wholly arrested,
when the core E is in its highest position, by 90
a detent-spring, p, fixed to flange B, engag-
ing with a fine toothed or milled edge of the
quadrant-shaped upper end, o', of the pendu-
lum o. A spring, q, is fixed to the under
side of the flange B in such position that the 95
upper end of the frame K will come in con-
tact with it when the core is raised to its
highest position in such manner as to increase

the pressure of the roller *i* against the carbon and more securely guard against the slipping down of the carbon when no further feed is required. The roller *h* is ratchet-toothed, and 5 a spring-pawl, *h'*, fixed to frame *B*, engages with it, the inclination of the teeth and pawl being such that when, by the descent of the core, the wheel moves past the pawl the latter holds a tooth of the wheel, which is thereby 10 caused to revolve for the purpose of giving a positive motion to the carbon, and so insuring the immediate commencement of its feed movement in case its own weight should be insufficient to overcome the inertia and friction of 15 the mechanism. When the core moves upward, the inclined nib of the pawl yields and slips on the teeth of the roller without turning it.

The upper carbon has a metal cap-piece, *r*, 20 fixed on its upper end, which serves both to weight it and to carry a metal roller, *s*, about which is wound a wire cord, *t*, attached by its other end to the tube *A*, and which unwinds as the carbon descends, for the purpose of 25 maintaining electrical connection between the tube *A* and the carbon in case the contact of the guide-rollers *g h i* should become inefficient.

The action of the lamp is as follows: The 30 carbons being in contact or sufficiently near for striking the arc on closing the circuit, the attraction of the solenoid for the core raises the latter until arms *e* and *e'* abut against plate *B*. The core carries up with it the upper carbon, (held between the three rollers, as above 35 described,) which is thus separated from the lower carbon the proper distance for establishing the arc. By the same upward movement the part *o'* of the pendulum is brought 40 against the detent *p*, whereby the roller *i* is prevented from turning, the spring *l* being now re-enforced by spring *q* to prevent the carbon slipping. As the carbons burn away, the resistance of the arc increases and the 45 strength of the current diminishes until the solenoid can no longer sustain the core in its highest position, whereupon it falls slightly, and by this motion the roller *h* is caused by

pawl *h'* to rotate, as above described, and impart to the upper carbon a downward movement in excess of the descent of the core which carries it. The same movement of the core liberates the pendulum from the detent *p*, whereupon the carbon will continue to descend by its own weight under the control of the 50 escapement and pendulum, which is caused to vibrate by the rotation of the roller *i*. This only continues until, by the shortening of the are, the strength of the current is increased sufficiently to enable the solenoid to raise the 55 core again, whereupon the vibration of the pendulum is stopped and the upper carbon held, as before.

I claim—

1. In an electric lamp, the combination, with 65 a solenoid in the lamp-circuit, of a tubular soft-iron core, through which the upper carbon passes, provided with guide-rollers to hold the carbon, and of automatic feed mechanism consisting of a pressing-roller mounted in a 70 frame pivoted to the core and pressed against the carbon by springs, and of an escapement and pendulum controlling the revolution of the said roller and a spring-detent for arresting its motion, whereby the feeding of the upper carbon is effected and governed, substantially as described, and shown in the drawings. 75

2. In an electric lamp, the combination, with the solenoid, tubular core, guide-rollers, rocking frame, escapement mechanism, pendulum, 80 and detent, combined for operation as described, of a pawl engaging with ratchet teeth on one of the guide-rollers not controlled by the escapement mechanism for the purpose of causing an initial motion to be imparted to 85 the carbon independently of the core and by the descent of the latter, substantially as described.

The above specification signed by me this 21st day of August, 1885.

OTTO ROMANZE.
